CLAIM

The ornamental design for a test strip unit, as shown and described.

DESCRIPTION

FIG. 1 is an exploded bottom perspective view of a test strip unit;

FIG. 2 is a bottom perspective view of the assembled test strip unit of FIG. 1;

FIG. 3 is a top perspective view thereof;

FIG. 4 is a top view thereof; and,

FIG. 5 is a side view thereof.

The broken lines immediately adjacent the shaded areas represent the bounds of the claim, and all other broken lines are included for the purpose of illustrating portions of the test strip unit that form no part of the claimed design. None of the broken lines form a part of the claimed design.
